UNITED STATES PATENT OFFICE.

JOHN LUKE BOYLE, OF BOSTON, MASSACHUSETTS.

COMBINED TALKING AND PICTURE-EXHIBITING MACHINE.

Application filed November 5, 1921. Serial No. 513,215.

To all whom it may concern:

Be it known that I, JOHN LUKE BOYLE, a citizen of the United States, residing at Boston, in the county of Suffolk and State of Massachusetts, have invented certain new and useful Improvements in Combined Talking and Picture-Exhibiting Machines, of which the following is a specification.

This invention is an improvement on my previous inventions listed below.

10 "Combined talking machine and stereopticon." Application filed May 16, 1919. Serial Number 297,715. Patented Aug. 12, 1919. Patent Number 1,313,190.

15 "Combined talking and picture-exhibiting machine." Application filed Dec. 28, 1914. Serial Number 879,280. Patented Aug. 12, 1919. Patent Number 1,313,214.

20 "Combined talking and picture-exhibiting machine." Application filed May 16, 1919. Serial Number 297,600 (Case pending).

25 "Combined talking and picture-exhibiting machine." Application filed Aug. 8, 1921. Serial Number 490,554 (Case pending).

30 This invention relates to a multiple record talking machine combined with a picture exhibiting or projecting mechanism which may be of the stereopticon type, adapted for delivering a lecture, speech, remarks or sounds of any kind which may be of considerable length, and exhibiting an extended series of appropriate pictures in properly timed relation to the several parts of the lecture or the like, thus providing a machine especially adapted for instructing, entertaining, advertising and other purposes.

35 An object of my invention is to provide an apparatus capable of handling a considerable number of talking machine records in automatic sequence, and controlling for exhibition in synchronism therewith a considerable number of pictures, the showing of which is automatically timed with reference to the delivery from the several records of the talking machine.

40 Another object of my invention is to adapt for automatic repeated operation the talking machine mechanism, the picture exhibiting mechanism, and the controller for the picture exhibiting mechanism, whereby the combined apparatus will automatically present the matter on the talking machine records and the respective pictures relating to same in picture exhibiting mechanism, in synchronism repeatedly, so that the apparatus may be set in operation and will run

45 for as long a period of time as desired, the speech, lecture, song or other matter that may be on the talking machine records and the respective pictures or written matter illustrating same, that may be in the picture exhibiting machine, being synchronously repeated and repeatedly illustrated automatically.

50 Another object of my invention is to provide a controller for the stereopticon whereby, if, because of poor electrical contact or for other reason, the stereopticon does not operate to present the next picture in the series at the proper period, at the next control period thereof by the controller, the stereopticon is caused to operate twice, whereby the stereopticon regains synchronism with the talking machine.

55 Another object of my invention is to provide a more compact machine.

60 Another object of my invention is to adapt the talking machine and the picture machine and cooperating parts so they may be operatively driven from one motor or a common drive shaft.

65 Another object of my invention is to secure the reliability of operation obtainable with a continuously running electric motor to drive talking machine and picture machine.

70 Another object of my invention, as shown in the modification herein, is to secure the reliability of operation obtainable with a continuously running electric motor to drive the picture machine, in addition to the continuously running electric motor for driving the talking machine.

75 Another object of my invention is to provide automatic means for setting the picture machine in operation, operated by a small automatically operated magnet.

80 Another object of my invention is to provide a simplified electric control for the picture machine, operated by the talking machine, having a small number of parts and wires.

85 My invention will be best understood by reference to the following description taken in connection with the accompanying illustrations.

90 Fig. 1 is a plan view of a combined talking machine and picture-exhibiting machine embodying my invention.

95 Fig. 2 is an end elevation of the multiple slide, dissolving view picture exhibiting machine.

driving screw and engaging the return screw. While the reproducer is being returned by the return screw, a new record is placed in playing position by the record holder 12 being turned on the shaft 10. Said record holder 12 has the pins 38 adapted to be engaged by the arm 39 for the movement of said record holder.

Means are provided whereby the reproducer stylus may be moved to the beginning of the new record, or it may be moved beyond the beginning of the story thereon and then moved back on the playing stroke without, however, engaging the record. Said means include the arms 40, one for each record, which are pivotally supported at 41 to a disc 42 secured to a hub by which it is fixed to the shaft 10 of the machine. Said arm 40 is extended upwardly above the record turn table and has a squared passage therethrough at its upper end, in which the stop member 43 is adjustably secured and fixed in adjusted position by a clamping screw. Said stop member terminates in an upturned portion which is adapted to be engaged by an arm 29 extended from the reproducer control arm during the latter part of its return movement, and it and the pivoted arm 40 are moved backward thereby to adjust the mechanism for the return or playing movement of the machine. Said stop member 43 is so positioned that it is engaged by the arm 29 to cause the return of the reproducer at the desired point, which may vary with different records.

The shifting of the reproducer carriage from the return to the feed screw is performed by mechanism set in operation by the lever 44 pivotally supported at 45 to a supporting standard of the machine. Said lever is formed with a vertical extension 46 having a terminal portion in proximity to said arm 40 bearing the stop member 43. Upon the backward movement of said arm 40 because of its engagement with the reproducer control arm, or equivalent, the lever 44 is moved to operate mechanism to cause the shifting of the reproducer carriage from the return to the feed screw.

When the reproduced is being returned the arm 29 which engages the stop member 43 is in a raised position. After it has engaged such stop member to cause the shifting of the reproducer carriage from the return to the feed screw, the arm 29 and the reproducer arm 23 and its control arm fall slightly and said arm 29 is then retained by the member 47, adjustably fastened in the arm 42 by thumb screw.

The reproducer is now being moved in a playing direction, without however, being in engagement with the record, and the arm 29 slides over said member 47.

When the reproducer has been moved a suitable distance on its playing stroke, the

arm 29 reaches the end of said member 47 and drops off, and the stylus of the reproducer may engage the record at the beginning of the story thereon, the beginning of the record having been previously located 70 and the record having been clamped to its turn table, which is locked in a predetermined position.

The reproducer stylus may be arranged to engage a stationary record at a prearranged 75 point in one of the cut lines on the record, the record then started turning, and by the time the stylus reaches the point at which the selection on record begins the record will be turning at the proper playing speed, thus 80 eliminating false tones at start of record.

The movement of the reproducer of the talking machine is multiplied in the controller arm for the stereopticon. The multiplying means here shown comprise the rack 85 70 (Figs. 1 and 4) slidable in the bearing 71 carried by the frame of the talking machine and engaged by the arm 72 fixed to the reproducer carriage by which said rack 80 is driven from said carriage.

A second rack 73 having magnified reproducer carriage motion and bearing the controller arm slidably arranged in the bearing 74. Multiplying means comprising the gears 75, 76 and 77 serve to multiply the motion of the rack 70 to said rack 73.

A controller arm 78 is fixed to said rack 73 and extends over the controller and bears at its extremity several spaced-apart depending fingers 79^a, 79^b, 79^c and 79^d (Fig. 4) which 100 bear contact members.

The stereopticon controller comprises the hexagonal drum 80 having as many sides as there are records of the talking machine, fixed to the extended portion of the talking machine shaft 10 and rotatable therewith. The controller drum is so fixed to said shaft that the flat side is on top, or under the controller arm, when corresponding record is in playing position. Each flat side bears the controller unit support 81 having tapered side walls in which the controller units are slidably received and clamped by the screws 82.

The controller unit comprises a block 83 of insulating material having tapered side walls and bearing on its top surface a plurality of conducting bars 84^a, 84^b, 84^c and 84^d (Figs. 4 and 1) which may extend the length of the block. The bar 84^a is adapted to be entirely 110 without lateral projections while said other bars may have projecting members as 85. Said projections may be either integral with said bars or separate therefrom and adjustably secured thereto as at 85, in which case, said bars 84^b, 84^c and 84^d are slotted to admit the passage therethrough of clamping bolts 86. and the block 83 is formed with slots 87 to receive said bolts.

Said finger 79^a of the controller arm 78 is 130

provided with a brush contact member 89, which is adapted to be in continual contact with said bar during the movement of said controller arm. Said other fingers 79^b, 79^c and 79^d are provided with a spring pressed trip contact member comprising the bar 91 pivotally connected thereto which is adapted to engage the projections 85 of said bars 84^b, 84^c and 84^d for accurate electrical contact therewith and ride over same during a certain extent of movement of said controller arm and thereafter snap away therefrom. All of said contact members 91 carried by said fingers 79^b, 79^c and 79^d are in permanent electrical connection with brush 89 through the metallic end portion of said arm, said end portion being insulated from the frame of the machine by the insulating bushing 93 interposed intermediate said arm 78.

The projections 85 are adapted to be located on said bars 84^b, 84^c and 84^d at points corresponding to points on the record at which it is desired to present a new illustration and the stereopticon control circuit is adapted to be made in succession through said bars 84^b, 84^c and 84^d, and then again in the same order for a purpose to be herein-after described.

As there are four controller bars to each controller unit and said bars have extended portions extending onto under side of said controller units, four collector rings 95^a, 95^b, 95^c and 95^d are arranged on the outer end of the controller concentric with said shaft 10 and separate leads extend therefrom to spring plates 96^a, 96^b, 96^c and 96^d in each support 81 which are in detachable connection with said bars, whereby corresponding bars in all units are connected to the same collector ring.

A standard 97 supported by the frame of the machine bears four independent brushes 98^a, 98^b, 98^c and 98^d which engage said collector rings and stereopticon controller leads are connected thereto.

Each unit support may be provided with an indicator as 99 and each unit may also be provided with a scale by which the unit may be adjusted with respect to the support and the projections 85 adjusted on the bars. The controller arm 78 is also provided with a pointer 100 movable over said scale whereby adjustments of the controller may be facilitated.

It is necessary that the controller arm 78 be raised from engagement with the controller at the end of its movement and before the talking machine is moved to present a new record for playing, and a new controller unit for same, to permit such movement. Means for accomplishing this result comprises the lever 102 fixed to the controller arm of the talking machine and extends under the arm 78. Said talking machine control arm, in its movement to elevated position, serves to also

raise the electric controller arm 78 to permit the turning of the controller. Said controller arm 78 for this purpose is pivotally supported at 103 to the rack 73. A rest for the arm 102 when in lowered position is shown at 102^a.

The picture machine comprises the two independent and similar slide holders 105 and 106 rotatably supported on the shaft or post 107 which is fixed at its ends to the frame 108 of the machine.

Each slide holder comprises the disc 105 (Figs. 2 and 3) upon which a plurality of spring plates 110, arranged in pairs, are supported. Slides are adapted to be movably held between each pair of plates. The periphery of the disc is provided with a plurality of pins 111 by which the slide holder is moved for the presentation of a new slide, and may also bear a series of numbers to denote the number of the slides in the total series of slides. The slides in the two holders are alternately numbered; that is, the slides bearing the even numbers are in one holder, and those bearing the odd numbers are in the other holder, and the slides in the two holders are alternately presented. An arm 112 fixed to the supporting post 107 beneath the slide holder bears the pointer 113 to indicate the slide 95 that is presented and a spring finger 114 carried by said arm is adapted to yieldingly engage the pins 111 to hold the slide holder in adjusted position.

The light house 115 (Fig. 5) and lenses 116 and 116^a are of usual construction. Two such houses and sets of lenses are provided, one for each slide holder, and are supported, one above the other, on the standard 117.

The slides contained in the slide holder 105 are adapted to be moved from the holder to a position between the lenses 116 and 116^a where they are supported by the table 125. For this purpose a frame 126 is provided. Said frame is carried by the rod 127 which is slidably supported by the bearing 128 secured to said post 107 above the slide holder. Said frame 126 is arranged so the plates in the slide holder may pass between its arms. For the presentation of a slide, the frame 115 is moved outwardly and the inner arm 126^a (Fig. 2) thereof engages the edge of a slide and moves it from the slide holder onto the table 125. In the withdrawing of the presented slide the outer arm of the frame engages the slide and returns it to its holder.

The rod 127 (Fig. 5) is reciprocated in its bearing 128 by the arm 130 which is fixed to a sleeve 131 supported on a supporting post 132 fixed to the frame of the stereopticon and retained in position thereon by the collars 133. A link 134 serves to pivotally connect the end of said arm 130 with the end of said rod 127 for its reciprocation.

The picture machine is driven from the 130

main driving shaft 20 of the talking machine as follows:—A sprocket wheel 135 mounted on the shaft 20 drives the sprocket wheel 136 by the link chain 137 (as shown in Figs. 1 and 5). A supporting post 20^a supports one end of the shaft 20. Said sprocket wheel 136 is secured to the shaft 138 supported by the posts 139. Said shaft carries the bevel gear 140 (Fig. 4) adapted to engage the large bevel gear 141, secured to the upright shaft 142, whereby the said shaft 142 with the gear 143, and the toothed wheel 144, both of which are secured theron, may revolve continuously, the upper end of shaft 142 being supported by bracket 145. An electro magnet 146 (Fig. 5) electrically connected with the controller by means described later, is arranged to move the arm 147 pivoted at 148. The end 20 of the arm 147 extends between and is adapted to engage the members 149 secured on the horizontal arm 150. Also secured on said arm 150 is a finger 151 pivoted at 152 and held in idle position against a stop 25 block by a spring, as shown in Fig. 5. The arm 147 is adapted to be moved by the magnet 146 to the position shown by the dotted lines in Fig. 5, being returned by the spring 153 thereby moving the arm 150 in its supports 154 and 155 together with the finger 151 with a reciprocating movement. The finger 151 is adapted to engage one of the four pins 156 which are mounted on the member 157 thereby turning said member 30 on its pivot 159 so that one of the equally spaced apart arms 158 of the member 157 engages a tooth of the moving wheel 144, thereby moving the said member 157 through the position shown by the dotted 35 lines in Fig. 5 together with the arm 160 upon which said member 157 is supported. Said arm 160 is pivoted on the post 161 and has secured to it a finger 163 extending downward and adapted to engage the arm 164, also pivoted on the post 161 immediately under the arm 160. The arm 164 is thereby moved causing a tooth portion 164^a of the arm 164 to be moved out of the notch 165. An idler gear 168 secured to an arm 50 169 which is pivoted at 170 to the arm 164, is moved to engage the driving gear 143, thereby starting the operation of the picture machine for the presentation of a new picture, by means hereafter described. The 55 said idler gear 168 is adapted to continually engage the gear 167. Said gear 167 and the disc 166 are secured to the main operating shaft 122 of the picture machine. The tooth 164^a of the arm 164 is adapted to ride 60 on the periphery of the disc 166, thereby holding the gears 168 and 143 in engagement until the other notch 165 in the disc 166 is moved to a position opposite the tooth 164^a of the arm 164, when said tooth 164^a 65 is caused to be moved into said notch by the spring 171, thereby disengaging the gears 168 and 143 and completing one operation of the picture machine. The arm 160 is returned to idle position against a stop 172 by a spring 173. A spring member 162 70 engages the member 157 to avoid unintended movement thereof.

The picture machine operates in the following manner:—The idler gear 168 (Fig. 5) engages the driving gear 143, thereby 75 turning the main operating shaft 122 of the picture machine one-half a revolution, said shaft being positioned by the notches 165. The sleeve 131 (Fig. 3) is provided with a cam member fixed thereto, having the projecting arms 174 and 175 (Fig. 5). A pin 176 and a tooth 177 are arranged on the disc member 166 which is secured to the main operating shaft 122. Said pin 176 is adapted to engage the cam arm 174, thereby 80 causing a picture slide in position for presentation on the support 125 to be returned onto the slide holder 105, by the arms 126^a (between which the slide is positioned) and cooperating members 127, 134, 130 and 131. 85 At this instant the tooth 177 engages one of the pins 111, thereby turning the slide holder 105 to so position same that, upon the pin 176 engaging the cam arm 175, a new slide will be moved out of the slide holder 90 105 into position for presentation on the support 125 by the arms 126^a and cooperating members 127, 134, 130 and 131. A pin 95 and finger mounted on the disc 166^a operates the upper slide holder in the same manner as the pin 176 and finger 177 on the disc 166 operates the lower slide holder. During one half a revolution of the shaft 122 the lower slide holder is operated and, on the other half revolution, the upper slide holder 105 is operated to move a new picture slide into position for presentation.

A circuit breaking means, or commutator, (Figs. 7, 8 and 9) in the electric control circuit for picture machine comprises three 110 conducting segments 178 (Fig. 9) spaced apart and electrically connected, also three other conducting segments 179, 180 and 181, the said conducting segments being mounted on a disc 182 of insulating material. Said 115 segments are adapted to be engaged by a brush having the arms 183, 184 and 185. Said brush is operated by the six-armed wheel member 186, and adapted to be turned on the shaft 132, between the stops 187, by 120 the four-armed wheel-shaped member 188 secured to the main operating shaft 122 of picture machine, said wheel member 188 having four arms 188^a which are adapted to engage the arms 186^a of the member 186. During one operation of the picture machine to present a new picture the shaft 122 turns one-half a revolution, together with the wheel member 188 (Figs. 7 and 8), thereby 125 causing the member 186 to be turned one- 130

third of a revolution, together with arm 190 to which the insulator 189 for the brush is secured. Also secured to the arm 190, and adapted to turn with same, is the three-sided member 191 (Fig. 8) adapted to be engaged by a spring fastened on the lower stop member 187 (Fig. 7). Said member 191 and its cooperating spring are adapted to avoid unintended movement of the brush holder arm 190 and the member 186.

The picture machine is set in operation to present a new picture in the following manner:—As the reproducer moves over the record, the arm 78 moves over the controller member 83 (Fig. 1), the brush 89 on the arm 79^a being in contact with the conducting member 84^a. The arm 78 moves along and the brush 79^b (Figs. 4 and 9) engages a contact finger 85 on the member 84^b, thereby completing the circuit through the magnet 146 and operating same to set the picture machine in operation by means previously described. Said magnet circuit is shown in Fig. 9, and is arranged as follows:—From ring 95^c to bar 84^c, through arms 79^a and 79^b to finger 85 on bar 84^b, from bar 84^b to ring 95^b, by the wire 192 to the commutator segment 179, by the brushes 183 and 184 to the inner segment 178 of commutator, then by wire 195 to magnet 146, and circuit completed by wire 196. During said operation of picture machine the arm 122 is turned one-half a revolution together with member 188, which causes the brush holder 190 to move the brush 183 one-third a revolution, or onto the next successive segment, 180, of the commutator. When the next contact finger 85 engages the brush on the arm 79^c, the circuit to the magnet 146 is again completed and the picture machine again operated.

As here shown, the picture machine is arranged to be self correcting or to be automatically returned to synchronism with the talking machine after a departure from synchronism.

If the electrical connection should fail at one of the contact points in the circuit to the magnet 146 and the picture machine consequently was behind the talking machine, means adapted to cause the picture machine to operate twice instead of once on the next regular operation of picture machine are provided to thereby return picture machine to correct relation with talking machine. Said means are as follows:—If the contact between the finger 85 on the bar 84^b (Fig. 9) and the brush on the arm 79^b fails, the magnet 146 will not operate to set the picture machine in operation and the picture machine will be behind the talking machine; but when the moving arm 78 reaches the point at which the brush on the arm 79^c engages the finger 85 on the bar 84^c, and this contact being good, the circuit is made by

the ring 95^c and wire 193 to the commutator segment 180, with which the brush arm 185 is in engagement, and as the brush spans the two segments 179 and 180 with the arms 185, 183 and 184, the magnet circuit is completed through the inner segment 178 and wires 195 and 196, and the picture machine is operated one operation. During this operation, the brush holder 190 shifts the brushes to the next successive segment of the commutator, that is, the brushes are now on segments 180 and 181. During the shifting of the brushes from one segment to another, the magnet circuit is broken due to the space between segments. It will be noted that the brushes have been shifted, the brush 185 being moved off of the segment 180 and the brush 183 being moved onto the segment 180, thereby reestablishing the magnet circuit through the brush arm 180 and again operating the magnet 146 to set the picture machine in operation a second time, to correct its relation with talking machine. The segment 180 remains alive until the brush 79^c passes the contact finger 85 on the bar 84^c. During the said second operation of the picture machine, the brush holder is again shifted and the magnet circuit thereby broken and, on the next contact of a brush with a finger 85, the normal operation of the picture machine occurs. The commutator brush arms 183 and 185 are adapted to always bridge two adjacent segments of commutator.

If the picture machine operates twice instead of once, due to faulty operation, consequently the picture machine will be ahead of talking machine and the brush arm on the commutator will be ahead one segment, so the magnet circuit will not be completed on the next contact at controller, but when the controller arm 78 reaches the succeeding contact the machines will be in step.

The operating and control mechanism for the two slide holders is so relatively arranged that the two parts of the picture machine will be alternately operated for the presentation of their slides and that when a slide is being presented by one part, a slide is in position for presentation by the other part, but is not illuminated. At the proper period the illumination of the first slide is gradually decreased and the second slide is gradually illuminated to obtain the dissolving feature, and when the first slide is dark the shifting of slides takes place.

The source of illumination is preferably incandescent lights enclosed in the light houses of which, in Fig. 6, 203 represents the light for the upper part, and 202 the light for the lower part of picture machine. The lamps are controlled by the following means:—An arm 197 is fixed to the main operating shaft 122 of the picture machine and is rotatable therewith. Said arm bears

the brushes 197^a, 197^b and 197^c which are electrically connected and insulated from said arm 197. A plate 198 is arranged concentric with, but independent of, said shaft 122 beneath said brush and is supported by the post 132. An inner collector ring 199 is carried by said plate, with which the brush 197^c is in continual engagement. An intermediate segment 200, associated with the circuit of the lamp 202 for the lower unit of the picture machine, is carried on the face of said plate and terminates at each end in bared resistance coils 200^a, the convolutions of which are adapted to be engaged by the brush 197^b during the movement of said arm 197, in the direction of the arrow, to first gradually increase the illumination of the lower lamp by cutting out resistance in the lower lamp circuit and then to gradually decrease the illumination thereof by cutting in resistance and, finally, by breaking the circuit. An outer segment 201 for the upper lamp is similarly arranged on said plate 198 and terminates in the resistance coils 201^a at each end, and said brush 197 is adapted to engage said segment and coils. It will be noted that the resistance coils of the outer and intermediate segments are opposite each other, whereby the illumination of one lamp is gradually decreased while that of the other is gradually increased, to provide for the dissolving of one picture into another. The circuit of one lamp is preferably broken during the period of maximum illumination of the other lamp.

A modified form of drive for the picture machine is shown in Fig. 10, the sprocket wheels 136 and link chain 137 (Fig. 5) being replaced by a belt pulley 204 adapted to be secured to the shaft 138 and driven by the pulley belt 205 from a separate motor, preferably an electric motor. This modified form permits the picture machine to be located in another part of the room from that of the talking machine, operating as previously described, and securing the reliability of operation obtainable with continuously running electric motors.

The electric service for the said talking and picture exhibiting machine may be supplied through a common "Time clock operated switch," whereby the said machine may be started and stopped automatically by said switch.

It may be seen that with the construction above set forth the necessary continued accuracy of presentation of the selections of the records and the slides is obtained.

It will be understood that while the illustrated machine shows a means whereby the matter on the talking machine records, and the pictures relating to same are automatically returned to synchronism after a departure from synchronous operation, that many other means may be arranged to ac-

complish the same general result, such as automatically causing the various parts of apparatus to be arranged in correct relation to each other, at prearranged points in its cycle of operation or at the end of each cycle of operation, such variations and modifications in the means by which the object is attained are within the scope of my invention.

It will also be understood that while I have here shown the pictures in the form of glass lantern slides, the pictures may be arranged in other forms, such as pictures being part of a long single strip of flexible film, or short sections detachably joined, so or individual pictures being part of individual films detachably supported on a carrier, and suitable means for displaying same in timed relation to matter on talking machine records, as herein described, without departing from the spirit of my invention.

While I have described a practical embodiment of my invention, the same is not limited to the details described, or the form, relation, or construction of parts, but that many and wide modifications may be made therein without departing from the spirit of my invention.

I claim:

1. Apparatus of the kind described, comprising mechanism for presenting in automatic succession the contents of a plurality of records, mechanism for presenting in automatic succession a series of still pictures to illustrate such records, a drive shaft, common to both of said mechanisms, an electric controller operated by one of said mechanisms for governing the other of said mechanisms so that it operates in synchronism with the first named mechanism, and means to automatically return said mechanisms into synchronous relation upon a departure therefrom.

2. Apparatus of the kind described, comprising mechanism for presenting in automatic succession the contents of a plurality of records, and automatically repeating said presentation, mechanism for presenting in automatic succession a series of still pictures to illustrate said records, and automatically repeating said presentation of pictures, a drive shaft common to both of said mechanisms, an electric controller adapted for automatic repeated operation, operated by one of said mechanisms for governing the other of said mechanisms so that it operates in synchronism with the first named mechanism, and means to automatically return said mechanisms into synchronous relation upon a departure therefrom.

3. Apparatus of the kind described adapted for automatic repeated operation, comprising a talking machine, having a reproducer adapted to operatively engage a plurality of records, in automatic succession,

to present the contents thereof, a picture machine adapted to present a plurality of still pictures, in automatic succession to illustrate the contents of said records, a drive shaft common to both of said machines, an electric magnet adapted to operate means for setting the picture machine in operation, means operated by the talking machine for controlling the operation of said magnet, whereby the picture machine may operate in synchronism with the talking machine, repeatedly, and automatically return into synchronous relation upon a departure therefrom.

JOHN LUKE BOYLE.
